(57) **CLAIM**

We claim the ornamental design for an enclosure for a mobile device, as shown and described.

DESCRIPTION

FIG. 1 is a top left front perspective view of an embodiment of an enclosure for a mobile device or portion thereof in a closed configuration.

FIG. 2 is a bottom left front perspective view of an embodiment of an enclosure for a mobile device or portion thereof in a closed configuration.

FIG. 3 is a top right back perspective view of an embodiment of an enclosure for a mobile device or portion thereof in a closed configuration.

FIG. 4 is a bottom right back perspective view of an embodiment of an enclosure for a mobile device or portion thereof in a closed configuration.

FIG. 5 is a front elevational view of an embodiment of an enclosure for a mobile device or portion thereof in a closed configuration.

FIG. 6 is a back elevational view of an embodiment of an enclosure for a mobile device or portion thereof in a closed configuration.

FIG. 7 is a left elevational view of an embodiment of an enclosure for a mobile device or portion thereof in a closed configuration.

FIG. 8 is a right elevational view of an embodiment of an enclosure for a mobile device or portion thereof in a closed configuration.

FIG. 9 is a top elevational view of an embodiment of an enclosure for a mobile device or portion thereof in a closed configuration.

FIG. 10 is a bottom elevational view of an embodiment of an enclosure for a mobile device or portion thereof in a closed configuration.

FIG. 11 is a left elevational view of an embodiment of an enclosure for a mobile device or portion thereof in an open configuration.

FIG. 12 is a right elevational view of an embodiment of an enclosure for a mobile device or portion thereof in an open configuration.

FIG. 13 is a back elevational view of an embodiment of an enclosure for a mobile device or portion thereof in an open configuration.

FIG. 14 is a front elevational view of an embodiment of an enclosure for a mobile device or portion thereof in an open configuration; and,

FIG. 15 is a front and back bottom right perspective view of an embodiment of an enclosure for a mobile device or portion thereof in an open configuration.

The broken lines in the drawings illustrate portions and features of the enclosure for a mobile device which form no part of the claimed design.
